UNITED STATES PATENT OFFICE.

BENJAMIN WOLHAUPTER, OF NEW ROCHELLE, NEW YORK.

RAIL-ANCHOR.

1,344,014.

Specification of Letters Patent. Patented June 22, 1920.

Application filed December 24, 1917. Serial No. 208,619.

To all whom it may concern:

Be it known that I, BENJAMIN WOLHAUPTER, citizen of the United States, residing at New Rochelle, in the county of Westchester 5 and State of New York, have invented certain new and useful Improvements in Rail-Anchors, of which the following is a specification.

This invention relates to a novel type of 10 rail anchor adaptable to rail bases of different widths.

A principal object of the invention is to provide a one-piece rail anchor which may be readily and economically manufactured 15 by conventional processes, while at the same time constructed to effectually prevent a rail from creeping in a longitudinal direction. Also the invention contemplates a one-piece anchor member adapted to have a driving fit upon the rail flange and adapted to 20 coöperate with the rail base in a manner to render the anchor thoroughly effective in its function of checking longitudinal movement of the rail, and not being subject to 25 relative displacement due to expansion and contraction of the rails, or vibration of the rail and track by the passing traffic.

A distinctive object of the invention is to 30 provide a new clamp type of rail anchor which may be quickly and readily applied to the rail by the simple act of driving the same onto the rail base from one side only of the rail, and which can be released by driving in the opposite direction. Also to provide a device 35 which will coöperate with both rail flanges in such a manner as to provide a maximum spring clamping engagement of both the anchor and the rail.

A further object of the invention is to 40 provide a clamp type of rail anchor wherein the clamping forces are so correlated with the rail flanges as to obtain a firm binding engagement with the rail base at a plurality of points of contact, preferably in alternating relation, whereby a maximum clamping effect is obtained.

The principle of construction embodied in 45 the improved rail anchor is susceptible of structural modification in a variety of forms without departing from the spirit of the invention, but for illustrative purposes there is shown in the accompanying drawings certain preferable embodiments, to wit:—

Figure 1 is an elevation of a rail anchor 50 constructed in accordance with the present

invention and shown in its initial position ready to be applied to the base of a rail.

Fig. 2 is a view similar to Fig. 1 illustrating a modification in the tail of the device.

Figs. 3 and 4 are views similar to the other views but illustrating a modification of the device to aid in resisting any tendency of the device to shake loose by moving back off the rail.

Fig. 5 is an elevation illustrating by full 60 lines only the relative position of parts when the anchor is driven firmly home upon the rail flange with the result of flexing or deflecting upwardly the tail of the device and the outer edge portion of the flange. 70

Fig. 6 is a detail elevation of a portion of a rail, showing in end elevation the improved anchor applied thereto and its relation to the rail supporting tie which acts as 75 the abutment against which the anchor bears.

Figs. 7, 8, 9 and 10 are similar views illustrating the adaptability of the improved anchor to rail bases of different sizes, that is, to rail bases of different widths as well as of 80 different thickness,—this series of views showing the anchor in its initial applied position before being forced to a driven fit.

Similar references designate corresponding parts throughout the several figures of 85 the drawings.

The improved anchor essentially consists of what may be termed a bar 1 formed with a spring tail member 2 constituting one end portion of the bar, and at its other end portion formed with a rigid rail flange engaging jaw C. This jaw includes the upper and lower members 3 and 4 respectively, integrally connected at one end by the fold or bight 5. The said jaw members have a 90 spaced relation to provide an ample rail-flange clearance space 6 for most sections of rail therebetween.

This construction of jaw adapts it to rail bases of many different widths and many 100 different thicknesses of rail flange and at the same time involves a formation which permits the jaw not only to be readily slipped over the rail flange, but also places the tail member under powerful spring tension which will cause both the upper and lower jaw members to bind tightly, respectively at the top and bottom of the rail flange. 105

It will be further observed that the up- 110

per and lower members 3 and 4 of the jaw are disposed so that the said jaw has a wide clearance over the outer portion of the rail flange of all standard weights of rails in use while the upper surface 12 and 13 of the bar is disposed so as to take an acute angle or incline with the bottom of the rail when applied to the latter.

This incline 12 and 13 in conjunction with the upper rigid member 3 of the jaw and the flexible tail member 2, is such that the effect of driving the rail anchor on to the rail flange, is to cause the lower corner 7 of the upper member 3 to ride inwardly and upwardly on the upper side of the rail flange, and the rail flange 14 to ride inwardly and upwardly on the lower surface 12 and 13 of the jaw, and to force the spring tail upward against the under side of the rail flange at 9. It will be seen that the incline 12-13 constitutes an inclined wedging surface whose angle diminishes with the flattening of the arched or bowed tail member. The result of this action is to render the wedging surface more acute and therefore more effective as the wedge is driven on.

The tendency of the spring tail, under these conditions, is to flatten out the bow or arch between 9 and 8 as indicated by dotted lines in Figs. 1 and 2, and for the edge of the rail flange to slide upwardly on the upper surface 12-13 of the lower member of the jaw, thus placing the rail flange at 14 under slight upward flexure as shown in dotted lines in the same figures.

The action, bringing about this condition, involves (in the form shown in the present application) the distinctive feature of a rigid rail flange embracing jaw which by its inward unyielding movement distorts upwardly the edge portion of the flange engaged thereby, combined with the resilient tail member whose upward spring pressure against the rail bottom, or opposite flange, increases as it in turn is distorted, by the driving on movement to assume a flatter form.

These gripping forces, exerted at widely spaced points both above and below the rail base, contribute to produce an engagement between the anchor and the rail base which will effectually resist any normal tendency to displace the rail anchor from the rail base.

As will have now been noted the anchor is driven onto the rail from one side thereof through the medium of blows from a driving tool or maul applied against the rigid jaw C and it can be released from the rail by driving it in the opposite direction, the driving tool or maul being applied at the driving head 15 of the tail end. When released the anchor and the rail return to normal conditions and the anchor is then ready to be used again.

By way of exemplifying the range of modification that may be resorted to in carrying forward the invention there is suggested in Fig. 2 of the drawing a form wherein the tail member 2 is tapered or thinned to save metal and also to increase the resiliency of the body of the bar beneath the rail base. And, in Fig. 3 of the drawings the tail member 2^a is shown as being inwardly deflected at an angle from the main body of the bar 1, and presenting a bearing surface 10 engaging the outer bottom corner of the rail flange, opposite the flange held under a deflecting pressure by the rigid jaw C. Also as shown in Fig. 4 the entire body of the bar beneath the rail base may be arched or bowed to form the upwardly deflected tail member 2^b. This latter modification also includes the suggestion of forming teeth or serrations 10^a for a positive interlock, if desired with a corner of one rail flange. However, both of the forms of Figs. 3 and 4 provide a construction which aids in resisting any tendency of the device to be loosened by vibration or by other ordinary or accidental causes.

In adapting the improved anchor to various sections of rails having bases of varying width and thickness no change or alteration therein is required, and in these adaptations and uses of the device the construction and action thereof remain the same as will be clearly understood by reference to the group of Figs. 7 to 10 inclusive.

Various other modifications of the invention may be utilized, and changes in the form, proportion and minor details of construction resorted to and the anchor may be manufactured by any of the various known processes, without departing from the scope or sacrificing any of the advantages of the invention.

I claim:—

1. A rail anchor comprising a body having at one end a rigid member presenting an inclined wedging part adapted to engage beneath the outer edge portion of one flange and a resilient member engaging the rail base.

2. A rail anchor comprising a body provided at one end with a rigid member having a wedging part disposed oblique to the plane of the rail base and adapted to bear upwardly on the outer edge portion of one flange, and a resilient member engaging the rail base.

3. A rail anchor comprising a body provided with a rigid member having a bearing for engagement on top of one rail flange and an inclined wedging part adapted to press upwardly the outer edge portion of the same flange, and a resilient member engaging the rail base.

4. A rail anchor comprising a body provided at one end with a rigid member having flange engaging elements arranged to exert an upward flexing pressure on the edge of a rail flange when driven thereon and retaining means for holding the device to the rail base. 65
5. A rail anchor comprising a body provided at one end with a rigid member having flange engaging elements arranged to exert an upward flexing pressure on the edge of a rail flange when driven thereon and spring retaining means for holding the device to the rail base. 70
- 10 6. A rail anchor comprising a body provided with a rigid member having flange engaging elements disposed in different vertical planes respectively above and below the rail flange and arranged to exert an upward flexing pressure on the edge of the flange when driven thereon, and retaining means for holding the device to the rail base. 75
- 15 7. A rail anchor comprising a body provided with a rigid member having flange engaging elements disposed in different vertical planes respectively above and below the rail flange and arranged to exert an upward flexing pressure on the edge of the flange when driven thereon, and spring retaining means for holding the device to the rail base. 80
- 20 8. A rail anchor formed of a single piece of metal provided at one end with a relatively rigid jaw having flange engaging elements arranged to exert an upward deflecting pressure on the edge of the rail flange when driven thereon, and a tail portion engaging the rail base under spring tension. 85
- 25 9. A rail anchor formed of a single piece of metal provided at one end with a relatively rigid jaw having flange engaging elements arranged to exert an upward deflecting pressure on the edge of the rail flange when driven thereon, and a tail portion engaging the rail base beneath the opposite flange under spring tension. 90
- 30 10. A rail anchor comprising a single bar of metal formed at one end with a rigid jaw embracing one rail flange and having flange engaging elements arranged to exert an upward deflecting pressure on the rail flange when driven thereon, and a resilient tail member engaging the rail base. 95
- 35 11. A rail anchor comprising a single bar of metal formed at one end with a rigid jaw having an upper member engaging the top of the rail flange and a lower inclined wedging surface engaging the lower corner of the flange, and a spring tail member engaging beneath the opposite flange under spring tension. 100
- 40 12. A rail anchor comprising a single bar of metal formed at one end with a rigid jaw
- 45 having an upper corner bearing for engagement with the top of the flange and a lower wedging surface engaging the lower corner of the same flange, and a resilient tail member engaging beneath the opposite rail flange under tension. 105
- 50 13. A rail anchor comprising a single bar of metal formed at one end with a rigid head having means for deflecting upwardly the edge portion of one rail flange when driven thereon transversely of the rail, and at its opposite end presenting a driving head for releasing the device by movement in the opposite direction. 110
- 55 14. A rail anchor comprising a single bar of metal formed at one end with a rigid jaw having means for distorting the edge portion of one flange upwardly when driven thereon, and a flexible tail member engaging the rail base under tension. 115
- 60 15. A rail anchor comprising a single bar of metal having rail flange engaging and distorting means maintained at an angle oblique to the plane of the rail base, and a rail base engaging tail member forming retaining means. 120
- 65 16. A rail anchor formed of metal bent at one end to provide a clamping jaw and at its other end a driving off head. 125
- 70 17. A rail anchor formed of a single piece of metal bent to form a clamping jaw for engaging with one rail flange and a one point frictional bearing member for engagement with the rail base. 130
- 75 18. A rail anchor having two bends only, one bend forming a clamping jaw and the other bend forming a driving off head for releasing purposes. 135
- 80 19. A rail anchor formed of a single piece of metal having two bends only, one bend forming a jaw having clamping engagement respectively with the top and the outer lower edge of one flange and the other bend forming retaining means engaging with the opposite rail flange at one point only. 140
- 85 20. A rail anchor formed of a single piece of metal bent at its ends, one end forming a rail flange embracing jaw and the opposite end forming a tail member having a one-point contact with the bottom of the opposite flange. 145
- 90 21. A rail anchor comprising a rigid jaw having unequal members adapted to clamp one rail flange, the shorter member arranged to bear on the top of one rail flange and the longer member arranged to have a one-point contact beneath the edge of the other rail flange whereby a head is presented for driving loose the rail anchor. 150
- 95 22. A rail anchor having a terminal jaw with unequal members disposed so as to rigidly engage one flange of the rail when said anchor is moved transversely of the rail, the longer member extending beneath

and beyond the opposite flange to permit the anchor to be driven transversely in the opposite direction and thereby loosened.

23. A rail anchor having a single terminal jaw whereby the anchor may be secured to the rail, and a driving off head at the other end whereby it may be loosened from the rail.

24. A rail anchor having a single terminal jaw whereby the anchor may be secured to the rail by a transverse movement in one direction, and a driving off head at the other end whereby it may be loosened from the rail by a reverse transverse movement.

25. A rail anchor having a terminal jaw with unequal members disposed so as to rigidly engage one flange of the rail base when said anchor is moved transversely of the rail, the longer member extending beyond the opposite flange whereby the anchor may be loosened when moved transversely in the opposite direction.

26. A rail anchor formed of a single bar of metal having at one end a single jaw adapted to clamp and grip one rail flange, and having at the other end a driving off head adapted to permit the release of said rail anchor from its gripping action.

30. 27. A rail anchor having a single rail flange engaging jaw and a flexible tail and adapted to grip the rail when forced in the direction of the tail, and to loosen when forced in the direction of the jaw.

35. 28. A rail anchor having a jaw so disposed as to distort one rail flange upwardly when moved transversely thereon and a tail portion extending from said jaw beneath the rail to and beyond the extreme edge of the opposite rail flange.

29. A rail anchor having a rigid jaw at one end and a tapered tail at the other.

30. A rail anchor formed of a single piece of metal having a rigid jaw at one end and 45 a tapered tail at the other.

31. A rail anchor comprising a jaw having gripping elements arranged to provide a two point contact with one rail flange, and a tail arranged to provide a one point contact with the bottom of the other rail flange.

32. A rail anchor comprising a single terminal jaw having unequal members, the end of the shorter member arranged to bear on 55 the upper portion of one flange and the longer member being bowed downward and

having a one-point contact under each flange of the rail.

33. A rail anchor comprising a jaw having unequal members, the shorter member arranged to bear on one flange of the rail and the longer member having a one-point contact on the bottom of each flange of the rail.

34. A rail anchor comprising a bar of metal bent or shaped to form at one end a single jaw to engage the top and lower edge of one rail flange, a shank extending therefrom beneath the rail, and a tail extending from said shank to engage at one point only the lower edge of the opposite flange.

35. A rail anchor comprising a terminal jaw and a flexible tail portion, so disposed as to cause the distortion of one rail flange and of the flexible tail portion when the device is moved onto said flange.

36. A one piece rail anchor comprising a rigid terminal jaw and a flexible tail portion so disposed as to cause distortion of one rail flange and of the flexible tail portion when said rail anchor is moved onto said flange.

37. A rail anchor having a jaw at one end adapted to flex the rail flange, and a flexible tail at the other end adapted to be flexed, when said anchor is forcibly applied to the rail.

38. A rail anchor comprising a body having a wedging surface for engagement beneath the edge portion of a rail flange, and means for causing the wedging action of said surface to increase as the anchor is forced on.

39. A rail anchor comprising a body provided with rail flange engaging means arranged to exert an upward flexing pressure on the edge of a rail flange.

40. A rail anchor having a jaw so disposed as to distort a rail flange upwardly when moved transversely thereon.

41. A rail anchor having a jaw so disposed as to distort a rail flange upwardly when moved transversely thereon, and a tail portion extending from said jaw beneath the rail.

In testimony whereof I hereunto affix my signature in the presence of two witnesses.

BENJAMIN WOLHAUPTER.
